James Twister of Washington Co. Md 9860X
Letters Patent

The schedule referred to in these Letters Patent, and making part of the same containing a description in the words of the said James Twister to himself of his improvement in the art of Tailoring:

To all to whom these presents shall come: Be it known that I James Twister Jr. in the County of Washington and State of Maryland, have invented a new and useful improvement in the art of Tailoring, and that the following is a full and exact description of the said art of Tailoring as invented or improved by me viz: Economical and improved systematic Tailors guide.

Description of the use of the square and improved systematic Tailors guide, the square supersedes the necessity of separate scales, the rule does not rely on the breast measure but makes every measure except the division of sleeve and shoulder measure cut itself. The balance measure of sleeve is relied upon as insuring to bring the fore part in its proper place, making good fits and giving ease and comfort to the customer, the proof measures may be used or not; but if practiced will give great satisfaction. The inventor of this work should not have thought of obtaining a patent for the art of fitting, owing to the numerous rules, that have been introduced with an eye single to that purpose - had it not been for the discovery of cutting a suit of clothes out from $\frac{1}{4}$ to $\frac{3}{4}$ of a yard less cloth, than the usual manner of cutting a coat out of $\frac{3}{4}$ to a $\frac{1}{2}$ a yard of less cloth. I have long thought that a system, marking off the whole coat would afford great facility in cutting to an old practitioner, and more especially to young beginners, without reference to saving; therefore, through practical experience discovering a complete system and mathematical principle in saving cloth. I determined to secure to myself a patent upon the principle of laying off the whole coat and pants, representing different sizes, according to width of cloth, and a rule of fitting tested by practical experience - explanation of sizes -

Draft No. 1. cloth six quarters $1\frac{1}{2}$ yard of cloth, size of coat. length of coat 36 inches, breast 33. waist 31. sleeve 33. Draft No. 2. cloth seven quarters

one and three eighths of cloth, length 40 inches, breast 35, waist 31, sleeve 35.

Draft No. 3. cloth six quarters one yard and a half of cloth length 39 inches, breast 37 waist 33, sleeve 34 $\frac{1}{2}$.

Draft No. 5. six quarter cloth coat and pantaloons, length of coat 40 inches, breast 36 inches, waist 32, sleeve 35, length of pantaloons 44 inches, knee 9, bottom 9, waist 32.

Draft No. 6. cloth six quarters one yard and a half of cloth, length 39 inches, breast 36, waist 32, sleeve 35.

Draft No. 7. cloth six quarters 2 yards of cloth frock coat, length 39 inches, breast 35, waist 32, sleeve 35.

Draft No. 8. cloth 29 inches wide, one and a half yards of cloth, length 39 inches, breast 35, waist 32, sleeve 35.

Draft No. 9. coat and pantaloons, cloth six quarters 3 yards of cloth 39 inches, breast 42, waist 40, sleeve 35.

Draft No. 10. cloth six quarters one and five eighths of cloth, length 40 inches, breast 36, waist 32, sleeve 35.

Draft No. 11. a frock coat without waist piece, 37 or 38 inches long, 36 breast 31, waist 2 yards and a quarter full pattern.

In addition to the above I make known that the principle of economy in saving cloth is claimed, viz: that the fore part is cut below the back or skirt securing the outside collar between them. From quarter cloth, the sleeves, cuffs, skirt and fore part are cut previous to cutting the back (See draft No. 1 & 2)

six quarter cloth in securing the skirt facing below at fore part (See drafts No. 6 & 10). To cut the frock coat without waist piece the back is cut opposite each other, the cloth is then split (See draft No. 11).

Proof measures have been introduced, I believe by Sitter's Patent, the principle I

have understood to start either from top of back or from back to back, my

proof measures divide the shoulder measure at A. 6. then pass over the top of

shoulder and over the measure and pass over the shoulder blade, thereby

dividing the fleshy or bony part of man more proportionally which I believe to

be, and claim as an improvement the accompanying drafts are to be taken

as part of my specification.

—Witness,

Peter Sitter Jr.

Richard Shackle,

1. Explanation of Skirt of Frock Coat. From 1 to 2 is length of skirt, 2 to 3 is $1\frac{1}{2}$ of waist, 3 to 4 is $1\frac{1}{2}$ of de - 3 to 5 is sweep from 5 to 2, placing the measure or string on 2 do, by placing the measure or string on 2, line drawn through

James Ziviser Jr.

9860X

1. 8.5 to 6 Spring for an over coat, spring of frock coat between six and seven.
1 to 8 is $8\frac{1}{2}$ placing the back on the skirt, then strap the bottom of skirt by placing the measure or string on 8.

2. Explanation of proof measure of fore part - From 1 to 2 is $5\frac{1}{2}$ of shoulder measure, 2 to 3 is $5\frac{1}{2}$ of do. do. 3 to 4 is $\frac{1}{2}$ of 3 and 2. The quirts on the back are the same. 1 to 6 is $1\frac{1}{2}$ of shoulder measure. 6 to 2 is first proof measure. 6 to 11 is $2\frac{1}{2}$ proof. 6 to 3 is $3\frac{1}{2}$ do. 6 to 7 is $11\frac{1}{2}$ do. 6 to 5 is $5\frac{1}{2}$ do. 6 to 10 is $6\frac{1}{2}$ do. 1 to 11 is $8\frac{1}{2}$ do. 1 to 12 is $9\frac{1}{2}$ do.

Explanation of proof under sleeve. From 5 to 7 is $8\frac{1}{2}$, 7 to 8 is width of back, 8 to 9 is $1\frac{1}{2}$ shoulder measure by coming from 8 to 7 and from 7 to 9. 10 to 9 is the measure of under sleeve.

130.9 yards
